CLAIM

The ornamental design for a merchandising display, as shown and described.

DESCRIPTION

FIG. 1 is a perspective view of a merchandising display showing our new design;

FIG. 2 is a front elevational view thereof;

FIG. 3 is a top plan view thereof;

FIG. 4 is a left side view thereof, the opposite side being a mirror image of the side shown; and,

FIG. 5 is a rear view thereof.

The broken lines shown in the drawings form no part of the claimed design.
